UNITED STATES PATENT OFFICE.

ABNER W. PYLE, OF HOPKINSVILLE, KENTUCKY.

FOLDING BED.

SPECIFICATION forming part of Letters Patent No. 734,363, dated July 21, 1903.

Application filed January 29, 1902. Serial No. 91,772. (No model.)

To all whom it may concern:

Be it known that I, ABNER W. PYLE, a citizen of the United States, and a resident of Hopkinsville, in the county of Christian and State of Kentucky, have invented an Improvement in Folding Beds, of which the following is a full, clear, and exact description.

My invention relates to improvements in folding beds of that class wherein a non-collapsible bed-frame is pivotally supported in a cabinet; and the primary object that I have in view is the provision of a portable structure which may be easily taken apart to facilitate storage and transportation and which may be assembled together for the several parts to occupy a solid firm relation to each other.

A further object of the invention is to combine with the pivoted bed-frame a counterpoise mechanism which occupies such a peculiar relation thereto as to subserve a two-fold purpose—*i. e.*, as a means to balance the bed-frame when it is being raised and when in its closed position and as a means for positively forcing the bed-frame to its fully-lowered position during the operation of opening the bed and also of positively locking the frame in its lowered position, thus effectually overcoming any tendency of the bed-frame to rise or fold accidentally.

A further object is to fold the doors of the cabinet entirely out of the way when the bed is in use; further, to secure ventilation of the cabinet, which is particularly desirable in warm weather, and to simplify the construction and to promote efficiency in the service of the structure.

With these ends in view the invention consists in the novel combination, construction, and arrangement of parts which will be hereinafter fully described and claimed.

Reference is to be had to the accompanying drawings, forming a part of this specification, in which similar characters of reference indicate corresponding parts in all the figures.

Figure 1 is a perspective view of a folding bed in its open condition and constructed in accordance with the principles of my invention. Fig. 2 is a vertical central section through the folding bed in its closed-up condition. Fig. 3 is a transverse section taken in the horizontal plane indicated by the dotted

line 3 3 of Fig. 2. Fig. 4 is a perspective view of the several parts composing my improved folding bed, the parts being disconnected or separated one from the other in order that they may be compactly arranged for storage or transportation. Fig. 5 is a detail sectional perspective view showing one means for detachably interlocking the cap-section and a side section of the knockdown cabinet which forms one part of the improved folding bed. Fig. 6 is a similar perspective view, partly in section, illustrating the means for interlocking the back frame or section and a side member or section to the base-section of the knockdown cabinet. Fig. 7 is a side elevation, on a small scale, of a modified construction of the front portion of the cabinet. Fig. 8 is a detail perspective view illustrating a part of the back member of the cabinet and the slideable headboard to show one keeper and the notch through which the keeper may pass in removing the headboard. Fig. 9 is a detail view showing the pivotal and detachable connection between a portion of the pivoted bed-frame and the intermediate headboard-section. Fig. 10 is a rear elevation of the improved folding bed, showing an arrangement of the counterpoise-weights by which the inertia of different weights may be successively taken up or imposed on the bed-frame. Fig. 11 is a detail cross-section showing the headboard partly raised to take up one of the weights or one weight of each of two groups of corresponding form, the bed-frame being supposed to be nearly raised. Fig. 12 is another cross-section with the headboard in its raised position, assuming that the bed-frame is lowered to its horizontal position. Fig. 13 is a detail horizontal sectional view through a portion of one side member of the cabinet and in a plane above the front rail 15 in order to show the binding engagement between said front rail and a side section of the cabinet.

A designates the casing or cabinet. B is the non-collapsible bed-frame, and C is the slideable headboard.

The bed-frame B consists of suitable side rails b, a foot-piece b', and a head-piece b'', and within this open skeleton frame is stretched the wire mattress D, or, if desired, any other suitable form of bed-bottom may

be employed. This bed-frame is pivotally supported at a point intermediate of its length in the lower part of the casing or cabinet A, and as one means of supporting the inner or lower end of said bed-frame I have provided the hinge-rod 5, the same extending transversely across the lower front part of the cabinet A and fitting in the inclined notches 6, the latter being provided in the side rails b of the bed-frame B. (See Figs. 1 and 2.) The hinge-rod 5 is indicated by dotted lines in Fig. 3 as extending transversely of the cabinet A, and this rod should have its end portions loosely received in suitable openings or other supports, which are provided in the side members of the cabinet, whereby the rod may be withdrawn from the cabinet and from engagement with the notches 6 of the bed-frame, thus making provision for dismounting or removing the bed-frame from the cabinet when it is desired to dismantle the folding bed for storage or transportation purposes.

The outer end portion of the bed-frame B is equipped with the foldable legs 7, the same being pivotally attached to the bed-frame, as indicated at 8 in Fig. 2, and said legs being united or tied together by the cross-bar 9. (Also shown in Fig. 2.)

To prevent the notched bed-frame from slipping out of engagement with the hinge-rod 5 during the operation of raising or lowering said bed-frame, I have provided the keepers or retaining-springs 10. The said springs are fastened to the inner opposing faces of the side rails b of the bed-frame, and the free ends of said springs are bent or arranged to extend across the notches 6, whereby said ends of the springs may engage with the hinge-rod 5, as shown by Fig. 2.

I will now proceed to describe the construction of the cabinet or casing A, which, it is desired to remark, has its several parts connected detachably together in a manner to facilitate assemblage or dismantling of the cabinet. This cabinet consists of the base-section a, the cap or top section or member a', the two side members or sections a² a³, (see Fig. 3,) and the back section or frame a⁴.

The side members a² a³ have their lower ends fitted within the side portions of the base-section a, said side members a² a³ having their lower extremities a⁵ seated upon the bottom portion of the base-section a. (See Fig. 2.) These side sections a² a³ are provided with the fastening-plates 11, which are provided with the notches 12, and in assembling the side sections within the base-section these notched plates 11 are arranged to

engage with the studs 13, as shown by dotted lines in Fig. 2, whereby the lower end portions of the side members have interlocking engagement with the base-section a. An upstanding front piece 14 is provided on the base-section a to sustain the shelf 15, the latter resting upon said front piece, as shown by Fig. 2. This shelf 15 is provided on its un-

der face with the fasteners 16, that are formed with beveled front ends adapted to be received in recesses, which are formed in said upstanding front piece 14, as shown by said Fig. 2. The shelf 15 is placed in position by turning it at an angle to the front piece 14 in order that the beveled ends of the fasteners 16 may enter the notches of said front piece, 75 and the side members a² a³ having been previously placed on the base-section this shelf is pressed downwardly, so that the rear edge of the shelf binds against the front edges of the side members, whereby the shelf is held 80 by the fasteners 16 against forward displacement relative to the front piece 14, and the shelf is thus adapted to similarly hold the side members a² a³ against displacement in a like direction.

The back frame or section a⁴ is skeletonized, as indicated more clearly by Fig. 4, and this frame is so proportioned that it will fit snugly to the side members a² a³, as shown by Fig. 3, and within the base a. This back frame or section is designed to have interlocking engagement with the side members a² a³ and the base-section a, and as one means for accomplishing this end I have shown said back frame or section a⁴ as having the notched or slotted plates 17, which are fastened to the side portions of the frame, so as to fit within the side members a² a³ and to have engagement with the studs 18, the latter being fastened to the side members. (See Figs. 1, 2, and 6.) Any suitable form of latch may be employed to fasten the back frame or section a⁴ to the base member a, but, as shown by Figs. 2 and 6, pivoted hooks 19 on the back frame a⁴ are arranged to engage 105 with eyes 20, that are attached to the base-section a.

The top member a' may be of any fanciful or suitable construction, and it is provided with the slots 21, (see Fig. 4,) adapted to receive the upstanding hook-shaped catches 22, as also shown by Fig. 5. After the side members a² a³ and the back member a⁴ shall have been assembled and interlocked the cap-section a' is fitted upon the other members 115 of the cabinet, so that the catches 22 will fit in the slots 21, and these catches are then turned crosswise of the slots in a manner to securely hold the cap-section upon the cabinet. Of course it is obvious that other forms 120 of locking devices may be adopted without departing from the spirit of the invention.

The side members a² a³ of the cabinet are provided with the doors 23, the same being hinged thereto, as at 24. In warm weather 125 the doors may be opened to the position indicated partly by dotted lines in Fig. 3, thus allowing a circulation of air around the head of the occupant of the bed.

The cabinet which I propose to employ 130 somewhat resembles the structure known in this art as a "wardrobe," although the finish and ornamentation of the cabinet may be varied within the skill of the constructor.

In order to employ a simple and comparatively cheap construction of the bed-frame and to secure a more ornate finish of the cabinet, I prefer to construct the cabinet with the sectional and foldable front, one form of which is shown by Figs. 1 to 3, inclusive, and another form is represented, on a reduced scale, by Fig. 7.

In the construction shown by Figs. 1 to 3, inclusive, the front consists of the rocking posts or columns 25 26, the wings 27, and the doors 28. Each post or column has one of the wings 27 made fast therewith, so as to extend laterally therefrom, and to the wing of each post or column is hinged, as at 29, one of the doors 28. The two columns 25 26 of the front are mounted to turn on vertical axes, which are afforded by the pintles 30, (indicated by dotted lines in Figs. 2 and 3,) and these posts or columns are arranged just in front of the side members $a^2 a^3$ of the cabinet A. In the folded position of the parts (shown by Figs. 2 and 3) the columns 25 26 are turned for the wings 27 to extend inwardly toward each other, and the doors 28 are disposed in the alined relation to one another and to the wings, as shown by Fig. 3. Any suitable catch may be employed to hold the doors in their closed positions. In order to use the bed, the doors are released and swung open. The doors may open as far as the position shown by Fig. 1, or the posts 25 26 may be turned around on their vertical axes to make the wings 27 occupy the rearwardly-projecting positions alongside of the cabinet shown by the dotted lines in Fig. 3, whereby the doors 28 may be opened to extend rearwardly of the cabinet, as indicated partly by dotted lines in Fig. 3, thus entirely opening the front of the cabinet and disposing the doors wholly out of the way.

In the modified construction shown by Fig. 7 I employ the two rocking posts 25^a 26^a, each of which is equipped with a wing 27^a; but in lieu of the two doors which are hinged individually to the wings of the two posts I employ a single door 31, that is hinged at 31^a to the wing of the post 25^a, the said door adapted to occupy an alined or abutting relation with the wing 27^a of the post 26^a.

I will now proceed to describe the slidable headboard C, which is mounted to move in a vertical path upon the back frame or section a of the cabinet. Any suitable means may be adopted for slidably confining the headboard in place; but in the knockdown portable construction of the folding bed contemplated by this invention I prefer to form notches 32 in the back frame a^4 , said notches providing for the passage of the keepers 33. These keepers are fastened to the slidable headboard C in positions to ride against the back frame a^4 , while the headboard itself travels against the front side of the back frame, as shown by Fig. 3; but when it is desired to remove the headboard C from the cabinet it is adjusted to a raised position in

order to bring the keepers 33 opposite to the notches 32, thus permitting the headboard to be moved laterally in order to withdraw the keepers through the notches. This headboard is provided in its back with a chamber or recess c , across which extends the confining-bar c' . The recess or chamber of the headboard is adapted to receive one or a series of counterweights, the same being indicated by the reference-letter D'. These counterweights are fitted in the chamber so as to be held in place by the bar c' , and, if desired, any one or more of the counterweights may be removed or placed in position, according to the load on the pivoted bed-frame B.

I employ an intermediate hinged connection between the weighted headboard and the pivoted bed-frame. By reference to Fig. 2 it will be seen that the bed-frame B is hinged by the rod 5 at a point intermediate of its length, so as to form a short section at the inner lower end of the bed-frame, which short section corresponds to the short arm of a lever. In opening or closing the bed the short section describes an arc of a circle the axis of which is the rod 5. The headboard C is limited to travel in a vertical path on the back frame or section of the cabinet, and the distance between the rod 5 and the headboard C is greater than the short arm or section at the inner lower end of the pivoted bed-frame. The intermediate hinged connection between the bed-frame and the headboard is represented by Fig. 2 in the form of a supplemental headboard E, the latter having a hinged connection, as at e, to the lower edge of the headboard and a pivotal and detachable connection with the head-section b^2 of the pivoted bed-frame. This detachable and pivotal connection is formed by notched plates 35, which are fastened to the end portions of the section E and are adapted to engage suitable studs 35^a, provided on the head-section b^2 . The intermediate section E is adapted to assume different positions with relation to the slidable headboard and the hinged bed-frame during the operation of raising and lowering the latter. In the closed condition of the bed (shown by Fig. 2) the head-section b^2 of the bed-frame lies in a horizontal position, while the intermediate section E occupies an inclined position between the vertically-slidable headboard C and said head-section b^2 , thus imposing the weight of the weighted head-section C upon the bed-frame to keep the latter in its closed position. In lowering the bed-frame B sufficient force must be exerted thereon to overcome the inertia of the weighted headboard C, and during the first half of the movement in lowering the bed-frame the head-section b^2 approaches the path of the headboard C, thus making the intermediate section E assume a position in line with the head-section b^2 of the bed-frame. As the lowering movement of the bed-frame continues, however, the head-section b^2 thereof is carried away from the path of the slidable head-

board, and during the last portion of the lowering movement of the bed-frame the intermediate section E assumes an abrupt angular relation to the head-section b^2 of the bed-frame and the headboard C, whereby the weight of the headboard is applied to the hinged bed-frame in a manner to positively force the latter to its lowered position and to lock said bed-frame in said lowered position, thus overcoming any tendency of the bed-frame to tilt in an upward direction. The detachable connection between the intermediate section E and the bed-frame, which is afforded by the plates 35, allows the bed-frame to be readily disconnected from the headboard when it is desired to dismantle the folding bed for storage or transportation.

Although I have shown and described the intermediate section E between the headboard and the bed-frame, I do not desire to limit myself to this particular construction, because I am aware that the solid piece may be omitted and suitable links or rods may be employed at the side portions of the headboard and the bed-frame. I have not considered it necessary to illustrate these links or rods, because the construction thereof will be evident to a skilled mechanic.

In Figs. 10 to 12, inclusive, I have represented a preferred embodiment of means whereby the inertia of the counterpoise may be imposed gradually upon the bed-frame in the operation of lowering the latter. The devices in this form of the invention are generically the same as heretofore described and include the cabinet A, the slideable headboard C, having the keeper-bar c' , the bed-frame, and the intermediate connection E. The weights D', however, are of different lengths, and they are preferably disposed in two groups—one on each side of the middle of the headboard—so as better to distribute the weight. The back frame a^4 of the cabinet is provided with a rest or cross bar 37, which is so placed that the weights D' will rest thereon and be sustained thereby when the bed-frame is raised. (See Fig. 10.) The weights D are provided with shoulders D^2 , and the weights are of different lengths, (see Figs. 10 to 12,) so that the shoulders lie at different distances from the rest-bar 37. The headboard C is provided with a cross-bar 38 at or near the lower end, and the shoulders D^2 of the weights lie in the path of the cross-bar when the bed-frame is raised and the headboard is lowered. On lowering the bed the headboard is raised and the bar 38 first engages with the shoulders of the short weight or weights D'. As the bed-frame is lowered farther the headboard is raised higher and engages with the next longer weights, and on lowering the bed-frame toward its horizontal position the longest weights are taken up by the cross-bar 38 of the headboard, thereby gradually and successively imposing the weights in opposition to the bed-frame. During the elevation of the bed-frame the weights are gradually

taken off the headboard because they will rest successively on the bar 37. I also contemplate the provision of rollers, as at 39, (see Figs. 2, 11, and 12,) which are mounted on the headboard C and are arranged to travel against the back frame a^4 of the cabinet, thus decreasing the friction and insuring easy movement of the parts.

Instead of arranging the fasteners 17 for the back frame and the sides in positions where they are visible on the inside of the cabinet, as in Fig. 2, I may place said fasteners 17^a and their studs 18^a on the back or rear wall of the cabinet (see Fig. 10) or in any other convenient position where they will not be exposed to view.

I may provide a single notch 32^a in the back frame of the cabinet to facilitate the removal of the headboard when desired.

Having thus described my invention, I claim as new and desire to secure by Letters Patent—

1. In a folding bedstead, the combination of a cabinet having a weight-supporting bar, a headboard slideable in said cabinet, a weight-pick-up rail movable with the headboard, a series of graduated weights resting on said bar and provided with shoulders which lie in the path of the pick-up rail, for successively imposing said weights on the headboard during the upward movement of the latter, and a bed-frame connected with said headboard.

2. In a folding bedstead, the combination of a cabinet, a headboard slideable therein, a weight-pick-up rail attached to the headboard for movement therewith, a bed-frame connected with the headboard, and two series of graduated weights supported in vertical positions within the cabinet near the respective sides thereof, each series of weights having shoulders disposed at different heights and all the shoulders lying in the path of the pick-up rail for successively imposing like weights of each series on the headboard in the upward movement thereof.

3. In a folding bedstead, the combination of an open front cabinet provided with vertical guides at its rear portion, a non-collapsible bed-frame within the open front thereof, a headboard slideable in the guides of the cabinet, a leaf connected pivotally to the headboard and the bed-frame, the rocking posts pivoted in the top and bottom portions of the cabinet on opposite sides of the path of the bed-frame, and each having a narrow rigid wing adapted to be folded backwardly against the sides of the cabinet, and doors hinged to said wings of the rocking posts.

4. In a folding bed, a knockdown cabinet having the side members fitted removably in the base-section, and a locking-shelf having interlocking engagement with the base-section and wedged between the latter and the side members for holding said side members firmly in place on said base-section, combined with a bed-frame, and means for detachably connecting said bed-frame to the cabinet.

5. In a folding bed, a knockdown cabinet comprising a base, top and side members, a skeletonized back having vertical guides, a locking-rail wedged between the base and the side members, and fasteners connecting the several parts firmly and detachably together, the whole forming a closed structure which is open at the front side thereof, combined with a non-collapsible bed-frame pivotally and detachably connected to the cabinet at a point in rear of the open front side thereof, said bed-frame being adjustable through the open front of the cabinet to horizontal and vertical positions, and a counterpoised headboard 15 slidably fitted in the back member and connected operatively with the inner end of said bed-frame.

6. A folding bed having a cabinet, a bed-frame pivotally and removably supported therein, a headboard slidably and removably mounted in said cabinet, an intermediate leaf permanently hinged to the headboard, studs or pins fixed to the sides of the bed-frame at

the inner end thereof, and plates attached to the leaf and having slots which loosely receive 25 the pins or studs and thereby connect the leaf pivotally and detachably to the bed-frame.

7. In a folding bed, a knockdown cabinet comprising a base, a top, side members connected detachably to the base and the top, a 30 back member having fasteners secured removably to the side members and the base, a front rail having a detachable interlocking engagement with the base and engaging frictionally with the side members for holding 35 them firmly in place, and a post mounted in the front rail and the top and carrying a door, combined with a bed-frame, and a counterpoised headboard.

In testimony whereof I have signed my 40 name to this specification in the presence of two subscribing witnesses.
